UNITED STATES PATENT OFFICE.

JOHN CREAHAN, OF PHILADELPHIA, PENNSYLVANIA.

BILLIARD AND OTHER CUES.

SPECIFICATION forming part of Letters Patent No. 233,325, dated October 19, 1880.

Application filed September 10, 1880. (No model.)

To all whom it may concern:

Be it known that I, JOHN CREAHAN, a citizen of the United States, residing in the city and county of Philadelphia, and State of Pennsylvania, have invented a new and useful Improvement in Billiard and other Cues, which improvement is fully set forth in the following specification and accompanying drawings, in which—

10 Figure 1 is a side elevation of a cue having my invention applied to it. Fig. 2 is an end view thereof, enlarged. Fig. 3 is a section thereof.

15 Similar letters of reference indicate corresponding parts in the several figures.

My invention consists of an elastic or flexible cushion applied to the butt-end of a cue, whereby said end is prevented from making a noise or being battered when thrown down

20 or struck on the floor.

Referring to the drawings, A represents a cue for billiards and other purposes, of ordinary form and construction.

B represents a block or piece of soft rubber 25 or other elastic or flexible material, preferably of hemispherical form, and constituting a cushion, which is secured to the butt-end of the cue A by means of a screw, C, passed through an opening centrally in the cushion, and having its head embedded therein, its point en-

tering the cue; but other means of attaching the cushion to the cue may be adopted—for instance, a socket formed in or attached to the cue and receiving portion of the cushion; a neck or tenon screwed into the butt; a socket 35 in the cushion receiving a neck or tenon on the cue; cementing or gluing the cushion to the cue, &c.

It is well known that billiard and other players often forcibly drop the butt-ends of their 40 cues on the floor, thus battering said ends and creating considerable noise, which is objectionable to other players and spectators. My cushion B prevents such results, and, serving as a guard for the butt-end of the cue, increases 45 the durability of the cue at said end.

Having thus described my invention, what I claim as new, and desire to secure by Letters Patent, is—

1. The elastic or flexible cushion B, adapted 50 to be attached to the butt-end of a cue, substantially as and for the purpose set forth.

2. A billiard or other cue having an elastic or flexible cushion on its butt-end, substantially as and for the purpose set forth.

JOHN CREAHAN.
